LAWN MOWER

Frederick Abel, Dayton, and Read Viemeister, Yellow Springs, Ohio, assignors to The Huffman Manufacturing Company, Dayton, Ohio, a corporation of Ohio

Application September 8, 1951, Serial No. 16,584

Term of patent 14 years

(Cl. D40—1)

To all whom it may concern:

Be it known that we, Frederick Abel and Read Viemeister, citizens of the United States of America, residing at Dayton, in the county of Montgomery and State of Ohio, and Yellow Springs, in the county of Greene and State of Ohio, respectively, have invented a new, original, and ornamental Design for a Lawnmower, of which the following is a specification, reference being had to the accompanying drawing, forming a part thereof.

Fig. 1 is a perspective view of a lawnmower, embodying our new design, and viewed at an angle generally from the front;

Fig. 2 is a perspective view of the lawnmower at an angle generally from the rear and with the handle moved to the opposite position to that shown in Fig. 1;

Fig. 3 is a plan view of the lawnmower with the handle broken away; and

Fig. 4 is a side elevational view of the lawnmower.

The design is characterized by the parts shown in full lines in the drawing.

We claim:

The ornamental design for a lawnmower, substantially as shown and described.

FREDERICK ABEL.
READ VIEMEISTER.
